United States Patent

Des. 236,652
Patented Sept. 2, 1975

236,652

COMBINATION FLASHLIGHT AND KEY CASE OR SIMILAR ARTICLE

Alexander Zalman, 8039 192nd St.,
Jamaica, N.Y. 11423

Filed Apr. 17, 1974, Ser. No. 461,547

Term of patent 14 years

Int. Cl. D3—01; D26—02
U.S. Cl. D48—24 A

FIG. 1

FIG. 2

FIG. 7

FIG. 3

FIG. 4

FIG. 5

FIG. 6

FIG. 1 is a top plan view of the combination flashlight and key case or similar article, showing my new design; FIG. 2 is a side elevational view taken from the front side thereof;

FIG. 3 is a side elevational view taken from the rear side thereof;

FIG. 4 is a bottom plan view thereof;

FIG. 5 is a side elevational view taken from the front end thereof;

FIG. 6 is a side elevational view taken from the rear end thereof; and

FIG. 7 is a view on a reduced scale.

I claim:

The ornamental design for a combination flashlight and key case or similar article, substantially as shown and described.
